UNITED STATES PATENT OFFICE.

GEORGE CLIFFORD HILL AND FRANK COOPER, OF SEATTLE, WASHINGTON.

MACHINE FOR GRINDING VALVES.

1,374,504.

Specification of Letters Patent. Patented Apr. 12, 1921.

Application filed February 14, 1920. Serial No. 358,610.

To all whom it may concern:

Be it known that we, GEORGE CLIFFORD HILL, a citizen of the United States, and FRANK COOPER, a subject of the King of England, both residing at Seattle, in the county of King and State of Washington, have invented certain new and useful Improvements in Machines for Grinding Valves; and we do hereby declare the following to be a full, clear, and exact description of the invention, such as will enable others skilled in the art to which it appertains to make and use the same.

This invention relates to machines for grinding valves, and particularly for grinding valves which are detachable from the cylinder block of gas engines.

The objects of this invention are to provide a machine for grinding movable valves by the operation of moving and rotating against each other the valve parts, which parts are moved by the machine to insure an even face on each part, the movement of one part being alternately in opposite directions.

Another object is to provide a machine whereby the parts of movable valves may be quickly ground together to assure a tight joint when the valve is closed, and whereby the parts being ground may be adjusted into the moving machine and removed therefrom without the stopping of the machine.

Another object is to provide a machine wherein a plurality of valves may be simultaneously ground, and any one of the parts of any of the valves in the machine may be removed without moving any of the other parts.

Another object is to provide a machine wherein the valve seat may be held rigid and moved or permitted to move at fixed periods, and the valve part is continuously rotated in opposite directions alternately, and whereby the valve seat is held against the valve portion by resilient tension while the parts are in contact for grinding.

Another object is to provide a machine for grinding with grinding material with facilities for applying the same.

The invention consists of the novel arrangement, structure and combination of parts as hereinafter more particularly described.

Three sheets of drawings accompany this specification, in which like reference characters designate like parts throughout.

Figure 1 is a front elevation showing the machine in operating position grinding two valves;

Fig. 2 is a side elevation; 60

Fig. 3 is a cross section in the center line of the chuck;

Fig. 4 is a plan view showing the driving mechanism which drives the valve stems upward and forward. 65

This invention is designed primarily for grinding the valves of Buick automobiles, in which engines are constructed with a removable cage or tube having one end provided with a valve seat. Both the intake and exhaust valves are similarly constructed, except that the inlet valve is made larger than the exhaust, as shown by the respective cages A and A' on Figs. 1 and 2.

By this machine the valve seat is held 75 exactly perpendicular by the table and adjusting fingers of the machine, and the valve stem is held exactly perpendicular in the chuck holder shown, which thereby assures the valve and seat when ground together to be in perfect alinement, and true joint between the parts will follow when the two parts are taken from the grinding machine and adjusted in their respective positions on the engine.

As the cage is released at stated periods during the grinding process, the friction of the moving valve will turn the cage a short distance, so that as the two parts are again thrown together by the releasing of the cam 90 action on the table below, the valve will grind in a different position in the seat, and the repeated reverse motions of the chuck with the valve assures an even grinding on every part of the adjoining faces. 95

While the grinding is proceeding, the operator at times places a mixture of emery powder or other grinding powder, preferably mixed with oil, on the valve and seat or on the inner wall of the cage, and as the 100 two parts are drawn apart and then thrown together the grinding solution evenly spreads over the faces being ground thereby; it is understood that a simple means may be provided for supplying this liquid 105 grinding solution by either pump or gravity.

As illustrated in the drawings, the invention is embodied in a machine having a base 35, a vertical frame 1, and a table 2', having a vertical apron 2 provided with vertical slots in slidable engagement with guides 40 on frame 1, and bolts 38 adapted 110

to slide through slots 39. The table 2' has openings over which are plates 3 to which the valves are secured, and having openings in which the valves A are adapted to sit. 5 Plates 3 are secured to table 2' by bolts 6 and sleeves 5'. On shelf 2' are fixedly mounted two bearing parts 8 and a sleeve bearing 45. A rock shaft 7 is mounted in bearing parts 8 and is provided with valve 10 engaging fingers 10 and operating levers 46 and 11. To operating lever 11 is pivoted a link 12 pivotally connected to a hand lever 13 with handle 20, which is in turn pivoted to a fulcrum rod 16 having notches 15 19 adapted to engage a fulcrum pin 18 in a slot 17 in table 2', through which rod 16 passes. A rod 44 having a head 43 slides in sleeve bearing 45, so as to engage lever 46 on rock shaft 7 and is normally depressed by means of the compression spring 44'. Mounted in suitable bearings on the frame 1 is a spindle 24 driven by a sprocket wheel 25 and chain 26 from drive wheel 29 and sprocket 27. Spindle 24 is provided 20 under table 2' with a cam 23 and a cam roller 42. Cam 23 contacts with a roller 30 mounted on a rod 31 pivoted to frame 1 at 32 and roller 30 in turn engages a nut head 33 mounted on table 2'. Cam roller 42 25 operates on head 43 of rod 44, which rocks shaft 7 through lever 46. Table 2' is normally held in its lowered position by rod 36 and compression spring 34 in co-operation with base 35. 30 On the upper part of frame 1 and mounted over the openings of table 2' and fingers 10 on rock shaft, and over the driving spindle 28 are vertical spindle bearings 48 similarly constructed with ball bearings 49. 35 The bearing over the driving spindle 28 carries a spindle 50 having on its lower end a bevel gear 51 engaging a similar bevel gear 52 on the driving spindle 28, and having on its upper end a crank lever 53 connected by 40 bolt pin 55 to driving arm 54, which in turn is pivoted by pin 56 to gear 57. Gear 57 engages and drives in successively opposite directions gears 58, which are connected to clutch carrying spindles 59 carried by the 45 bearings 48, located over the table openings 4. 50

The clutches carried by spindles 59 are illustrated in detail in Fig. 3, in which the bottom of spindle 59 is shown provided with 55 a slot 60. The clutch consists of a tube 63 having bushing 62 bored to receive the slotted end of spindle 59, and a pin 61 secures tube 63 and bushing 62 passing through slot 60 of spindle 59. A spring 64 between head 62 and bearings 49 depresses the clutch against the upward thrust of a spring 68 located within tube 63 and between bushing 62 and a slidable bearing 65 secured to the lower end of spindle 59 by 60 a wire ring 66 seated in adjacent grooves in

spindle and bearing. Head 69 is provided with a vertical bore 75 adapted to receive a valve stem 83, and the upper end of this bore is enlarged as at 71 to receive the lower end of spindle 59 and a compression 70 spring 74 mounted on a spindle 73 having a flange 73', and extending below said flange into the smaller bore 75. A washer 72 is interposed between the ends of spindles 59 and 73. Transversely of head 69 near its 75 lower end are two recesses adapted to receive pins 77, adapted to enter the slot of a valve stem 83, and provided with heads 78 having concave seats for balls 79. Pins 77 are further provided with compression 80 springs 82 tending to withdraw pins 77 from the bore 75. A sleeve 80 having a bore 73 adapted to receive a compression spring 86, and a shoulder 87 for one seat for said spring 86 is fitted over head 69. A washer 85 85 is interposed between spring 86 and the bottom of tube 63. The lower inner edge of sleeve 80 is beveled as at 81. Over sleeve 80 a knurled sleeve 90 is held by a wire collar 91 in a groove 92 cut in sleeve 80, and rotates freely on said sleeve 80 by reason of the ball bearings 93. A bronze washer 88 is seated between shoulders 87 and 89 of sleeve 80, and head 69, respectively.

In operation, the valves to be ground are 95 placed on plates 3 and the latter secured to table 2' by means of the bolts 5. In placing the valves on table 2', the rock shaft 7 is operated and lifts fingers 10 by means of hand lever 20, which being pulled up by the operator, engages a notch in rod 19 with fulcrum pin 18, depresses link 12, which in turn pulls lever 16 attached to shaft 7. The ends of the valve stem are secured in the chuck head 69 by means of pins 77, which are withdrawn from bore 75 to permit the entrance of the valve stem by raising sleeve 80 against the compression spring 86, thus permitting balls 79 to drop back against bevel 81 and permitting the pins 77 to be 100 forced out by springs 82. With the valve stem in place, sleeve 80 is released, and, descending, forces in balls 79 and pins 77, so that the latter enter the slot of the valve stem and secure the stem in non-rotatable 105 relation to the head 69. It will be apparent that spring 74 operates to depress head 69 relatively to spindle 59, operating on said spindle through washer 72. Spring 68, on the other hand, tends to elevate the clutch 110 relatively to spindle 59 against the buffer spring 64. Knurled sleeve 90 enables the operator to adjust sleeve 80 while the machine is in motion. The valve stems secured in the chucks will be rotated by the latter in 115 successively opposite directions by the operation of the gears 58 and 57 operated by the crank shaft 54, crank 55, and beveled gears 51 and 52. At the same time the valve casings secured to table 2' will be success- 120 125 130 135

sively raised and lowered by the latter as it is operated by means of the cam 23 on spindle 24 driven by sprockets 25 and 27 and chain 26. Periodically with the raising and 5 lowering of table 2' as above, eccentric roller 42, also on spindle 24, will rock shaft 7 by means of lever 46, thus momentarily releasing the valves from fingers 10 and permitting the valves to turn slightly and 10 seat themselves.

It will thus be apparent that this machine rotates the valve stem in successively opposite directions under varying tensions with regard to the valve seats, successively seats 15 and reseats the valve heads in the valve seats, and permits the rotation and readjustment of the valve seats relatively to the valve heads all automatically, while at the same time means are provided for operating 20 the attaching devices for both valves and valve stems independently and while the machine is in motion. Friction material, such as emery paste, may be fed between the valve heads and valve seats, 25 either by hand or by a suitable feeding device, and other modifications of particular structural features will readily suggest themselves to those skilled in the art, within the scope of the present invention.

30 What we claim is:

1. In a machine for grinding portable valves, means for holding the valve seat rigid and means for releasing the holding means at predetermined periods, with means 35 for holding the valve portion against the seat with resilient pressure, and means for rotating the valve in alternate directions for predetermined limits of movement.

2. A machine for grinding valves, having 40 means for holding the valve seat, means for releasing the seat from the machine without stopping the operation of the machine, means for holding and rotating the valve and valve stem, means for releasing the 45 stem and valve from the machine without stopping the same, and means for inserting the seat and valve in place in the machine for grinding without stopping the machinery of the moving means.

50 3. A machine for grinding portable valves, comprising a frame, a table slidably mounted on said frame having openings over which valves to be ground may be placed, a rock shaft mounted on said table 55 having fingers extending over said open-

ings, adapted to engage and secure said valves on said table, means for manually rocking said rock shaft and lifting said fingers, means for automatically raising and lowering said table and rocking said rock 60 shaft, valve stem clutches vertically mounted over said table and adapted to resiliently hold said valve stems, and means for rotating said valve stem clutches in alternately opposite directions. 65

4. In a machine for grinding portable valves having a frame, a vertical slideable table mounted on said frame, and adapted to receive the valves to be ground, means for successively releasing said valve stems from 70 engagement with said table, comprising valve engaging fingers carried by said rock shaft, and means for successively raising and lowering said table and releasing said fingers, and means for rotating the valve 75 stems in successively opposite directions.

5. In a machine for grinding valves, means for holding and rotating the valve and valve stem comprising a shaft, a sleeve 80 slidably supported on said shaft, a head carried by said sleeve having a bore to receive the valve stem and radially slideable members adapted to engage the valve stem in said bore, a sleeve rotatably and slidably mounted on said head and means for controlling 85 said radially slideable members operated by said last mentioned sleeve.

6. In a machine for grinding valves, means for holding and rotating the valve and valve stem comprising a shaft, a sleeve 90 slidably mounted on said shaft, elastic means controlling said sleeve, a head carried by said sleeve having a bore to receive a valve stem, elastic means in said bore to engage a valve stem, radially slideable members carried in said head adapted to engage the valve stem, elastic means tending to withdraw said radial members from said bore, a second sleeve carried by said head rotatable and slideable thereon, elastic means 95 to hold said second sleeve depressed and means intermediate said second sleeve and said radial members, whereby the elevating of said sleeve will permit the withdrawal of said radial members from said bore and 100 the release of the valve stem.

In testimony whereof we affix our signatures.

G. CLIFFORD HILL.
FRANK COOPER.
